COMBINED LAWN MOWER AND GRASS CATCHER

Clifford E. Cressy, 7006 Indianapolis Blvd.,
Hammond, Ind. 46324

Filed Oct. 13, 1971, Ser. No. 189,071

Term of patent 14 years

Int. Cl. D15—03

U.S. Cl. D40—1 B

Fig. 1

Fig. 2

Fig. 3

Fig. 4

Fig. 5

FIG. 1 is a perspective view of a combined lawn mower and grass catcher embodying the present design;

FIG. 2 is a side elevational view of the combined lawn mower and grass catcher shown in FIG. 1;

FIG. 3 is a top plan view of the combined lawn mower and grass catcher shown in the preceding figures;

FIG. 4 is a side elevation opposite that shown in FIG. 1; and

FIG. 5 is a rear elevation thereof.

I claim:

The ornamental design for a combined lawn mower and grass catcher, substantially as shown and described.
